UNITED STATES PATENT OFFICE.

FRANK R. ZINKE, OF WAUKESHA, WISCONSIN.

RAILROAD TIE.

Application filed October 26, 1923. Serial No. 670,866.

To all whom it may concern:

Be it known that I, FRANK R. ZINKE, a citizen of the United States, and resident of Waukesha, in the county of Waukesha and State of Wisconsin, have invented certain new and useful Improvements in Railroad Ties; and I do hereby declare that the following is a full, clear, and exact description thereof.

- 10 This invention relates to railroad ties. Objects of this invention are to provide a railroad tie which is formed of cement, baked clay or similar permanent material, which is internally reinforced so as to supplement the inherent strength of the material with the additional strength of the binding reinforcing portions.

Further objects are to provide a railroad tie which is of approximately standard shape, except that the edges and ends are preferably rounded to facilitate handling and to prevent chipping, which is provided with a plurality of spike receiving members into which the spikes may be driven in the usual manner without danger of splitting or cracking the tie, which is so constructed that the spike receiving portion, when worn, may be readily removed and replaced, in which parallel side and end bracing bands are provided, and in which transverse reinforcing members join the side portions of the band, and reinforce the railroad tie adjacent the spike receiving members.

Embodiments of the invention is shown 35 in the accompanying drawings, in which:—

Figure 1 is a plan view of the tie showing the position of the rails.

Figure 2 is an enlarged sectional view on the line 2—2 of Figure 1.

40 Figure 3 is an enlarged sectional view on the line 3—3 of Figure 1.

Figure 4 is a fragmentary view corresponding to a portion of Figure 2 showing a modified form of construction.

45 The railroad tie comprises a body portion 1, which is preferably of moulded concrete or clay, and if of clay, is thoroughly baked to secure the requisite hardness. This body portion has embedded therein and completely covers a reinforcing band 2 which forms a closed loop, that is to say, which is provided with parallel side members and with end members, so as to form a rectangular figure of slightly less size than that of the body portion 1 of the tie. This reinforcing band is preferably formed of channel iron,

as clearly shown in the sectional view Figure 3, and thus materially adds to the strength and rigidity of the tie. At spaced points, preferably adjacent the rail receiving portion, a pair of transverse bars 3 join the side walls of the band 2, as shown in Figures 2 and 3.

The body portion is provided with holes therethrough adjacent the transverse bars 3, and these holes are substantially of rectangular cross section and taper inwardly toward their center on the opposed sides of adjacent holes, as clearly shown in Figure 2. Within these holes, blocks 4 of wood 70 are inserted during casting or moulding operation and are contoured to fit such holes, as may be clearly seen from Figure 3. These wooden blocks are thus securely retained within the tie and provide means for receiving the spikes 5. In order to further strengthen the structure, a transverse rod 6 is provided between each of the pairs of bars 3 and join the said members. If desired, a central rod 7, see Figure 1, may be 80 provided to join the central portion of a side portion of the band 2.

In using the device, the rails 8 are placed thereon, as shown in Figure 1, and the spikes 5 are driven into the wooden blocks 4, as 85 clearly shown in Figure 2. It is intended that these wooden blocks shall be made of such cross sectional area that they will accommodate a wide or narrow rail. It is to be noted that when the spikes are driven 90 into the wooden blocks that they tend to expand the blocks and force such blocks more tightly into engagement with the sides of the holes or openings through the tie.

In the modified form shown in Figure 4, 95 a slightly different construction of wooden block is employed. This construction is particularly applicable for baked clay ties or for repairing worn ties. In this form of the invention, the body portion 1, the band 100 2, the transverse 3 and the transverse rods 6 are identically the same as those previously described. However, the wooden block 9 is formed of a member having a gradually tapered upper portion and having initially a 105 straight bottom portion provided with a slot at its lower end. This lower member is slipped into the hole through the body portion and a wooden wedge 10 is driven upwardly into the bottom part so as to expand this lower portion of the wooden block 110 and cause it to wedge or bind within the

tapered lower portion of the hole through the body of the tie, as clearly shown in Figure 4.

It will be appreciated that when the tie is formed of a baked clay or similar member that the wooden block must be inserted after the baking operation. It is preferable, therefore, as shown in Figure 4, to provide wooden blocks which may be readily inserted after the baking process and which may be securely locked in position.

It is to be further noted that if the wooden blocks of the first described tie should become worn through repeated use, these blocks may be readily replaced. The worn blocks are driven from the holes in the body portion and new blocks of the form shown in Figure 4, are inserted and the wedge 10 is driven into place, thus locking the new blocks in position.

It is to be further noted that a railroad tie constructed in accordance with this invention may be most readily handled and the rail may be most readily secured thereto.

It is further to be noted that if the railroad tie should wear adjacent the rails, it is merely necessary to prop the rails upwardly a slight distance from the tie and pour fresh cement beneath the rails. This fresh cement will soon harden and combine with the concrete tie or baked clay tie and thus furnish a fresh and properly positioned bearing surface for the rails in place of the worn surface.

Although the invention has been described in considerable detail, it is to be understood that the invention may be variously embodied and is, therefore, to be limited only as claimed.

It sometimes happens that the ballast and cross tie are frozen and are practically immovable. Under these conditions if it is necessary to adjust the height of the rail, the spikes are withdrawn and shims placed under the rail to hold it at the exact height desired. Thereafter, the spikes are redriven and the rail is consequently secure in its correct position without the necessity of loosening the concrete tie from the frozen ballast. In concrete cross ties, as heretofore constructed, this has been impossible and the consequence was that adjustment of the rails had to be done when the cross ties could be loosened.

Although the cross tie is adequately rein-

forced with metallic members, nevertheless, it is admirably adapted for use on railroads where electrical circuits are employed which include the tracks as the spikes are insulated by the plug which receives them.

I claim:

1. A railroad tie comprising a moulded body portion, a closed band located within, and completely covered by said body portion and having parallel, spaced side walls, a plurality of transverse members connecting said side walls, said body portion having openings therethrough, and wooden blocks located within said openings and adapted to receive spikes.

2. A railroad tie comprising a moulded body portion, a closed band located within, and completely covered by said body portion and having parallel, spaced side walls, a plurality of transverse members connecting said side walls, said body portion having openings therethrough adjacent certain of said transverse members, and wooden blocks located within said openings and adapted to receive spikes.

3. A railroad tie comprising a moulded body portion, a closed metal band embedded within said body portion and completely covered thereby and having parallel side walls, a plurality of spaced transverse bars joining said side walls, said body portion having openings therethrough adjacent said bars, and a plurality of wooden blocks located within said openings and contacting with said bars, said blocks being adapted to have spikes driven therein.

4. A railroad tie comprising a moulded body portion, a closed metal band embedded within said body portion and completely covered thereby, said band having end portions and parallel side portions and conforming approximately to the outline of the tie, a plurality of spaced transverse bars joining the side portions of said band, said body portion having openings therethrough adjacent said bars, a plurality of wooden blocks located within said openings, and transverse rods joining the side walls of said band and located between said bars.

In testimony that I claim the foregoing I have hereunto set my hand at Waukesha, in the county of Waukesha and State of Wisconsin.

FRANK R. ZINKE.
